UNITED STATES PATENT OFFICE.

CHARLES F. STODDARD, OF BOSTON, MASSACHUSETTS, ASSIGNOR TO
AMERICAN PNEUMATIC SERVICE COMPANY, OF DOVER, DELAWARE,
A CORPORATION OF DELAWARE.

PNEUMATIC-DESPATCH APPARATUS.

No. 805,168.

Specification of Letters Patent.

Patented Nov. 21, 1905.

Application filed May 13, 1904. Renewed March 28, 1905. Serial No. 252,528.

To all whom it may concern:

Be it known that I, CHARLES F. STODDARD, of Boston, in the county of Suffolk and State of Massachusetts, have invented certain new and useful Improvements in Pneumatic-Despatch Apparatus, of which the following is a specification.

My invention relates to new and useful improvements in terminals for pneumatic-despatch-tube apparatus, and especially to such apparatus wherein large carriers are used for the transmission of mail-matter, merchandise, and the like.

The object of my invention is to produce a machine simple in construction and efficient in operation.

My invention consists of certain novel features hereinafter described, and particularly pointed out in the claims.

In the accompanying drawings, which illustrate a construction embodying my invention, Figure 1 is a longitudinal section through the terminal with parts in position to receive a carrier. Fig. 2 is a similar view through the terminal after a carrier has been received. Fig. 3 is a cross-section at the forward end of the receiving-chamber of the terminal on the line X X, Fig. 2. Fig. 4 is a cross-section through the rear end of the receiving-chamber on the line Y Y, Fig. 2.

Like letters of reference refer to like parts throughout the several views.

The main transmission-tube A is located in alignment with the compression or receiving chamber A² of the terminal and beyond the slotted casing A', through which the pressure passes into the return-tube A³. Located on the upper side of the compression or receiving chamber A² is the cylinder D⁴, connected with the compression or receiving chamber A² by the pipe C⁵, and located within said cylinder is the piston D², connected by the rod D³ with the piston-valve D', which in turn is connected by the rod D⁵ to the rod D⁷ by the pivot-joint D⁶. The rod D⁷ is pivotally connected to the finger D⁸ at E, and this finger D⁸ swings on the bracket E², to which it is pivotally connected at E', and said finger normally extends into the path of travel of the discharging-carrier, Fig. 2. The air supplied for operating the inner and outer gates B B² in the terminal enters through the pipe C into the valve-casing D and is conveyed into

the tops of the inner and outer cylinders B⁶ B⁵ by the pipes C' C² and operates the pistons B⁴ B⁷, to which are respectively connected the gates B B² by the piston-rods B³ B'. The carrier coming into the compression-chamber A² is brought to a stop by the compression of the air in front of it as the gate B² is closed. This pressure passes through the pipe C⁶ into the cylinder D⁴ and forces the piston D² to the end of the cylinder D⁴, as shown in Fig. 2. This movement of the piston D² moves the piston-valve D' from the position shown in Fig. 1 to that shown in Fig. 2 and also moves the finger D⁸ into the position shown in Fig. 2. The air-supply entering the valve-casing D through the pipe C passes through the pipe C' to the upper side of the piston B⁷ in the cylinder B⁶ and closes the gate B. As the piston B⁴ reaches the lower end of the cylinder B⁶ it passes the port P, which admits the pressure to the under side of the piston B⁷ in the cylinder B⁵ through the pipe C⁴. This pressure raises the piston B⁷ to the upper end of the cylinder B⁵, causing the raising of the gate B², which is connected to the piston B⁷ by the piston-rod B'. The pressure from the line A passes through the port P² in the gate B into the chamber A² back of the carrier and forces the carrier out of the chamber A² onto the table A⁴. In the position of the parts shown in Fig. 2 the finger D⁸ is in the path of the carrier, which strikes it as it comes onto the table A⁴. This finger D⁸ moves the piston D' from the position shown in Fig. 2 to that shown in Fig. 1, thereby opening the pipe C' to the atmosphere to allow the pressure in it and the cylinder B⁶ to exhaust to the atmosphere. The pressure in the pipe C then passes through the pipe C² into the cylinder B⁵ above the piston B⁷ and forces it down into the position shown in Fig. 1. As the piston B⁷ reaches the lower end of the cylinder B⁵ it passes the port P', which allows the pressure to pass through the pipe C³ to the under side of the piston B⁷ in the cylinder B⁶, thereby raising the piston B⁴ to the position shown in Fig. 1, which places the apparatus in position to receive another carrier.

The pipe C⁵ is connected to the cylinder D⁴ and is for the purpose of balancing the piston D² when the machine is not in operation and is in communication with the inner end of the receiving-chamber A².

A^3 is a suitable buffer or stop for the carrier as it reaches the end of the table A^4 .

E is the floor-line, and A^5 , A^6 , A^7 , and A^8 are suitable supports.

5 The operation and construction so far described are similar to that shown and described in United States Letters Patent No. 742,516, dated October 27, 1903, and granted to the American Pneumatic Service Company, 10 of Dover, Delaware, as my assignee.

The inner end F' of the receiving-chamber A^2 and the slotted casing A' are constructed so that the area of the cross-section is enough greater than the area of the cross-section 15 through the largest part of the carrier to allow the air compressed by the carrier coming into the receiving-chamber A^2 to escape around the corner, so that there will be practically no cushioning effect until the carrier 20 is completely into the compression-chamber A^2 . F shows the point at which this enlarged section shown in Fig. 4 emerges into the circular outer end F^2 shown in Fig. 3, which is the shape of the outer end of the compression-chamber A^2 . The object of this enlarged section is to insure the carrier coming 25 completely into the compression-chamber A^2 before it is stopped by compressing the air in front of it. It is obvious that if the carrier 30 should be brought to a stop so far back in the compression-chamber A^2 that the gate B^3 could not close it would preclude the further operation of the machine.

I do not limit myself to the arrangement 35 and construction shown; as the same may be varied without departing from the spirit of my invention.

Having thus described the nature of my invention and set forth a construction embodying the same, what I claim as new, and desire 40 to secure by Letters Patent of the United States, is—

1. In a pneumatic-despatch-tube apparatus, 45 a transmission-tube, a terminal, and a receiving-chamber in said terminal and having its inner end constructed of greater area than the largest part of the cross-section through the carrier entering therein to allow the air ahead of the carrier to escape around said carrier 50 thereby preventing the cushioning of said carrier in the inner end of the receiving-chamber to allow the carrier to enter the receiving-chamber.

2. In a pneumatic-despatch-tube apparatus, 55 a transmission-tube, a terminal, and a receiving-chamber in said terminal having its inner end constructed of greater area than its outer end in which the carrier is cushioned so as to allow the escape of air around said carrier 60 thereby preventing the cushioning of said carrier in the inner end of the receiving-chamber to allow the carrier to enter the receiving-chamber.

3. In a pneumatic-despatch-tube apparatus,

a transmission-tube, a terminal, a receiving-chamber in said terminal having its inner end constructed of greater area than its outer end in which the carrier is cushioned so as to allow the escape of air around said carrier thereby preventing the cushioning of said carrier in the inner end of the receiving-chamber to allow the carrier to enter the receiving-chamber, and means for cushioning said carrier in the outer end of said terminal.

4. In a pneumatic-despatch-tube apparatus, 75 a transmission-tube, a terminal communicating with said tube, a receiving-chamber in said terminal, an inner gate between the transmission-tube and the receiving-chamber and normally open, an outer gate between the receiving-chamber and the atmosphere and normally closed, an inner and an outer cylinder, a piston in each cylinder connected respectively to said inner and outer gates, an air-supply for operating said pistons to move said gates and 80 normally holding said inner gate open and said outer gate closed, communication between said cylinders and said air-supply, a valve for controlling communication to each cylinder alternately, and mechanism operated 85 by the air compressed ahead of the carrier in the outer end of the receiving-chamber for operating said air-controlling valve to allow the air-supply to open the outer gate and close the inner gate, the inner end of the receiving-chamber being constructed of larger area than the outer end to allow the escape of air around 90 said carrier thereby preventing the cushioning of the carrier in the inner end of the receiving-chamber to allow the carrier to enter 100 the receiving-chamber.

5. In a pneumatic-despatch-tube apparatus, 105 a transmission-tube, a terminal communicating with said tube, a receiving-chamber in said terminal, an inner gate between the transmission-tube and the receiving-chamber and normally open, an outer gate between the receiving-chamber and the atmosphere and normally closed, an inner and an outer cylinder, a piston in each cylinder connected respectively to said inner and outer gates, an air-supply for operating said pistons to move 110 said gates and normally holding said inner gate open and said outer gate closed, communication between said cylinders and said air-supply, a valve for controlling communication to each cylinder alternately, mechanism operated by the air compressed ahead of the carrier in the outer end of the receiving-chamber for operating said air-controlling valve to allow the air-supply to open the outer gate and close the inner gate, the inner end of the receiving-chamber being constructed of larger area than the outer end to allow the escape of air around 115 said carrier thereby preventing the cushioning of the carrier in the inner end of the receiving-chamber to allow the carrier to enter the receiving-chamber.

ceiving-chamber, and mechanism operated by the carrier leaving said terminal for operating said air-controlling valve to allow the air-supply to open the inner gate and close 5 the outer gate.

6. In a pneumatic-despatch-tube apparatus, a transmission-tube, a terminal, and a receiving-chamber in said terminal having its inner end constructed with a circular bottom to conform to the shape of the carrier and an enlarged top to allow the air ahead of the carrier to escape around said carrier thereby preventing the cushioning of said carrier in the inner end of the receiving-chamber to 5 allow the carrier to enter the receiving-chamber.

7. In a pneumatic-despatch-tube apparatus, a transmission-tube, a terminal, a receiving-chamber in said terminal having its inner end constructed with a circular bottom to conform to the shape of the carrier and an enlarged top to allow the air ahead of the carrier to escape around said carrier thereby preventing the cushioning of said carrier in the inner 5 end of the receiving-chamber to allow the carrier to enter the receiving-chamber and having its outer end constructed of circular

form, and means for cushioning said carrier in said outer end.

8. In a pneumatic-despatch-tube apparatus, 30 a transmission-tube, a terminal, a receiving-chamber in said terminal having its inner end constructed with a circular bottom to conform to the shape of the carrier and an enlarged top to allow the air ahead of the carrier to 35 escape around said carrier thereby preventing the cushioning of said carrier in the inner end of the receiving-chamber to allow the carrier to enter the receiving-chamber and having its outer end constructed of circular 40 form, a gate closing the outer end to the atmosphere and against which the air is compressed ahead of the carrier for cushioning the carrier, and means for opening said gate to allow the discharge of the carrier from the 45 terminal.

In testimony whereof I have signed my name to this specification, in the presence of two subscribing witnesses, this 4th day of May, A. D. 1904.

CHARLES F. STODDARD.
